[57] **CLAIM**

The ornamental design for a CTR terminal for vehicle
navigation, substantially as shown and described.

DESCRIPTION

FIG. 1 is a top perspective view of the CTR terminal
for vehicle navigation according to my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view thereof taken from the left
side, top and front; and

FIG. 9 is a perspective view thereof taken from the
right side, top and rear.

FIG. 1

FIG. 2

FIG. 3

FIG. 4

FIG. 5

FIG. 6

FIG. 7

FIG. 8

FIG. 9
